UNITED STATES PATENT OFFICE.

FRED LEE CANOTT, OF PORTLAND, OREGON.

STORM CURTAIN.

1,410,457.

Specification of Letters Patent. Patented Mar. 21, 1922.

Application filed January 7, 1921. Serial No. 435,684.

To all whom it may concern:

Be it known that I, FRED LEE CANOTT, a citizen of the United States, and a resident of Portland, in the county of Multnomah and State of Oregon, have invented a new and Improved Storm Curtain, of which the following is a full, clear, and exact description.

This invention relates to improvements in storm curtains, an object of the invention being to provide a curtain of this character which is peculiarly adapted for use on automobiles, but which may be applied to various other vehicles.

15 A further object is to provide improved mounting for the curtain and to provide a guide therefor which may be readily moved to operative position when the curtain is in use, or which can be quickly folded up and 20 swung out of the way when the curtain is not needed.

25 A further object is to provide an improved curtain and mounting therefor which will be simple and practical in construction, strong and durable in use, neat and attractive in appearance and which will efficiently perform the functions for which they are intended.

With these and other objects in view the 30 invention consists in certain novel features of construction, and combinations and arrangements of parts, as will be more fully hereinafter described and pointed out in the claims.

35 In the accompanying drawings—

Figure 1 is a view in front elevation of my improved curtain in applied position.

Figure 2 is a top plan view of the curtain and its support.

40 Figure 3 is a fragmentary view in section on the staggered line 3—3 of Figure 2.

Figure 4 is an enlarged fragmentary detail view of the lower end of one of the supports illustrating the curtain in locked 45 position.

Figure 5 is a fragmentary view illustrating the method of locking the guide members to a support.

Figure 6 is a reduced view in front elevation illustrating the parts in folded position.

Referring in detail to the drawing, I have illustrated in Figure 1 the inside of an automobile body, the reference numerals 1 and 2 representing the driver's seat and the 55 rear seat of the car respectively. The side wall 3 of the body provides mounting for

the usual door 4 just behind the driver's seat 1. The top 5 of the car is supported by the usual metal framework 6 and my improved curtain 7 is illustrated in applied 60 position suspended from the horizontal side bar 8 of the top supporting framework 6.

It is to be understood that the curtain 7 is intended to be used over the door 4 to supplement the other curtains or rain 65 shields commonly employed, but for the purpose of more clearly illustrating the construction of my improved curtain the other protecting devices have not been shown.

A pair of brackets 9 of substantial U- 70 shape are fixed to the frame bar 8 or to any other suitable support, which may be provided above the door 4. These brackets at the upper edges of their intermediate portions are formed with recesses 10. Inwardly 75 extending lugs 11 at the upper ends of the recesses 10 and outwardly extending lugs 12 at the lower ends of the recesses are provided for a purpose which will hereinafter appear. The lower edges of the intermediate 80 portions of the brackets are formed with outwardly extending recessed flanges 13.

Plates 14 are hingedly connected at their lower edges to tubular guide members 15. At one of its upper corners each plate is 85 formed with a T-shaped extension 16 located in the recess 10 of the bracket 9 between the lugs 12, the arms of the T engaging under the lugs 11 and holding the plate firmly in place. The edges of the plates 14 90 engage the intermediate portion of the brackets 9, the recessed flanges 13 straddling the edges of the plates and lending further rigidity to the connection of the plates and brackets.

95 The upper edges of the plates 14 are recessed to receive the ends of a conventional spring curtain or shade roller 17 which carries my improved storm curtain 7. The tubular guides 15 hingedly depend from the 100 plates 14 and are provided at their lower extremities with cut-away portions 18 to accommodate the upper edge 19 of the door frame or side wall 3 of the car. At each side of the door the frame is formed with 105 a slot 20 which receives a locking tongue 21 slidable vertically in the lower end of the tubular member 15 and operated by a suitable handle 22 extending inwardly over the door frame and movable through a vertical 110 slot 23 in the tube.

This construction permits the guide mem-

bers to be removably locked in vertical position, one on each side of a door 4. The adjacent faces of the tubular members 15 are longitudinally slotted from end to end 5 as indicated at 24.

The curtain 7 is cut away at its lower corners to expose the ends of the curtain bar 25. The bar 25 includes enlarged ends 26 movable in the tubes 15 and reduced portions 27 adjacent each end movable through the slots 24. At their lower ends the members 15 are formed with vertically disposed recesses 28 communicating with the slots 24 so that the reduced portions 27 of the 10 curtain bar 25 may be moved into the recesses 28 holding the curtain down against the action of the spring roller.

To more securely lock the casing in case of severe storms I provide a key 29 suspended by a chain 30 from one of the plates 20 14. This key may be passed through a suitable perforation 31 in the wall of one of the members 15 and also through a registering perforation 32 preferably in the form 25 of an eyelet, which is provided in the edge of the curtain 7.

It will be seen that the construction above described cooperates to form a rainproof closure over the door 4. The edges of the 30 curtain 7 are slidable in the tubes. The top 5 of the automobile extends over the curtain roller and prevents rain from entering over the top of the curtain. A depending apron 33 depends from the curtain bar 25 between the reduced portions 27 of the bar and prevents any leakage under the curtain.

When the curtain is not in use, it may be 40 rolled up and improved means are provided on the tubular guide members 15 for locking them in folded position below the curtain roller. One of the members 15 is provided adjacent its hinged end with a pair of arms 34 adapted to straddle the free end of the other member 15 when these guide members are in folded position. The last-mentioned guide member is provided adjacent its hinged end with a hinged aperture arm 35 adapted to engage 45 over the handle member 22 on the other guide member so that the two members are locked in the folded horizontal position 50 illustrated clearly in Figure 6.

One of the members 15 is slightly shorter 55 than the other member so that the parts may be folded with convenience.

For the convenience of the occupants of 60 the rear seat the curtain 7 may, if desired, be provided with a transparent section, such as 36.

While I have illustrated one of the preferred embodiments of the invention, it will be apparent that various slight changes might be made in the general form and 65 arrangement of the parts described without

departing from the invention, and hence I do not limit myself to the precise details set forth, but consider myself at liberty to make such changes and alterations as fairly fall within the spirit and scope of the appended claims. 70

I claim:

1. The combination with a suitable support, of a curtain roller mounted therein, guide members hingedly depending from the support, a shade mounted on the roller and guided in its movement by the guide members, and means for supporting the guide members in folded horizontal position when the shade is rolled up. 75

2. The combination with a suitable support, of a curtain roller mounted in the support, a pair of vertical slotted tubular guide members hingedly depending from the support, a shade mounted on the roller, devices at the lower edge of the shade movable in the guide members, the side edges of the shade being movable in the slots, and means for locking the guide members in folded horizontal position when the curtain 80 is rolled up.

3. The combination with a suitable support, of a curtain roller mounted in the support, a pair of vertical slotted tubular guide members hingedly depending from the support, a shade mounted on the roller, devices at the lower edge of the shade movable in the guide members, the side edges of the shade being movable in the slots, and means carried by the hinged end of each 95 guide member adapted to removably engage with the free end of the other guide member to lock the guide members in folded horizontal position. 100

4. The combination with a support, and 105 a stationary base below the support, of a pair of plates depending from the support, tubular guide members hingedly depending from the plates and having vertical slots in their adjacent faces, a shade mounted in the support, devices at the edges of the shade movable in the guide members, and means 110 associated with the free ends of the guide members adapted to removably engage the base. 115

5. The combination with a support, and a stationary base below the support, of a pair of plates depending from the support, tubular guide members hingedly depending from the plates and having vertical slots 120 in their adjacent faces, a shade mounted in the support, devices at the edges of the shade movable in the guide members, locking tongues mounted to slide vertically in the lower ends of the guide members, said base 125 having slots therein receiving the tongues, said tubular guide members having short vertical slots therein, and handles connected to the locking tongues and movable through the slots. 130

6. The combination with a suitable support, and a base located below the support, of a curtain roller mounted in the support, a spring held curtain on the roller, vertical slotted tubular guide members hingedly connected to the support and removably connected to the base, a curtain bar adjacent the lower edge of the curtain, said bar including a reduced portion adjacent each end 5 slidable in the slots, and enlarged end portions slidable in the tubular members, said curtain being cut away in its lower corners to expose the reduced portions. 10
7. The combination with a suitable support, and a base located below the support, 15 of a curtain roller mounted in the support, a spring held curtain on the roller, vertical slotted tubular guide members hingedly connected to the support and removably connected to the base, a curtain bar adjacent the lower edge of the curtain, said bar including a reduced portion adjacent each end slidable in the slots and enlarged end portions slidable in the tubular members, said curtain being cut away in its lower corners to expose the reduced portions, and a depending apron on the lower edge of the curtain carried by the curtain bar and located between the reduced portions thereof. 20 25

FRED LEE CANOTT.
